INFLATABLE SHOE FOR AIRCRAFT

Willson H. Hunter, Akron, Ohio, assignor to The
B. F. Goodrich Company, New York, N. Y., a
corporation of New York

Application September 10, 1943, Serial No. 501,783

7 Claims. (Cl. 244—134)

1

This invention relates to inflatable shoes for preventing the accumulation of ice upon aircraft surfaces when exposed to ice-forming conditions and especially to such shoes adapted for mounting on thin-section leading edges of airfoils.

While the removal of ice has been successfully accomplished heretofore on airfoils having relatively thick-section leading edges by inflatable shoes mounted on such leading edges, nevertheless airfoils having relatively thin-section leading edges have presented a troublesome condition with respect to such ice removal especially at the immediate leading edges. Such a condition arises from the difficulty in fracturing the ice formation or cap along the immediate leading edge and in unbalancing and moving the broken pieces of ice for effective removal by the airflow.

Objects of the invention are to provide for effectively preventing the accumulation of ice on bodies having thin-section leading edges; to provide for effective breaking of ice caps at the leading edge while providing for moving broken ice laterally away from the leading edge for most effective removal in the air flow; to provide for relatively high stretchability immediately at the leading edge while providing restraint of stretchability immediately to the sides thereof and while providing for effective movement of the side portions to remove ice, and to provide simplicity of construction, effectiveness of operation and convenience of manufacture.

These and other objects and advantages of the invention will be apparent from the following description.

In the accompanying drawings which form a part of this specification, and in which like numerals are employed to designate like parts throughout the same,

Fig. 1 is a perspective view in section of an inflatable shoe mounted on an airfoil having a thin-section leading edge, and constructed in accordance with and embodying the invention, parts being broken away,

Fig. 2 is a view like Fig. 1 but showing the shoe in an inflated condition,

Fig. 3 is a plan view from the top of the shoe, and

Fig. 4 is a sectional view of the attachment of the margin of the shoe to the airfoil, parts being broken away.

In the arrangement shown in Fig. 1 an inflatable shoe 10 including elastic material such as resilient rubber or other rubber-like material, is mounted on an airfoil 11 such, for example, as

2

an airplane wing, having a thin-section leading edge 12.

The shoe 10 comprises a tube portion 13 extending longitudinally along the leading edge 12 and stretchable portions 14 and 15 extending from the sides of the tube portion 13 to the respective margins 16 and 17 of the shoe, which margins are attached to the airfoil 11 in a manner to provide for maintaining the shoe in a condition of tension therebetween for preventing undue bulging and wrinkling of the exposed surface of the shoe. As shown especially in Fig. 4, each of the margins 16 and 17 are provided with a fabric strip 18 united to the rubber thereof and folded to accommodate a metallic strip element 19 extending throughout the margin, the strip element 19 being desirably in the form of a flat or oval wire.

For attaching the shoe 10 to the airfoil 11 screws 20 are disposed through the shoe structure just inside the wire 19 and are tapped into hollow threaded rivets 21 set into the metal surface or other structure of the airfoil. The arrangement is such that the wire 19 is adapted to bear against the screws 20 to maintain the shoe in a condition of tension between its upper and lower margins 16 and 17. The margins are desirably tapered in section at the portions 16a and 17a extending beyond the wires 19 to provide fairing for a smooth airflow across the airfoil, and these tapered portions may be provided with a cover strip 16b of rubber and are preferably adhered to the surface of the airfoil by a suitable adhesive such, for example, as rubber cement. However, the tube portion 13 and the stretchable portions 14 and 15 are not adhered to the airfoil 11, so as to permit relative movement therebetween during inflation of the tube 13.

The tube portion 13 at the leading edge 12 includes an inner wall 22 and an outer wall 23 of suitable elastic material such as resilient rubber-like material and a reinforcing fabric element 24 disposed in the inner wall 22 and in longitudinally extending side regions 25 and 26 of the outer wall 23. In the outer wall 23 the margins of the fabric are spaced apart at 31 and 32 for providing an intermediate region 27 of the outer wall 23 at the leading edge 12 having relatively high stretchability by virtue of the elasticity of the material thereof. At the same time, the fabric provides for restraining the stretching of the elastic material immediately to the sides at the regions 25 and 26 of the tube portion 13 in addition to restraining the stretching of the inner wall 22 thereof. A suitable conduit 28 of flexible

material is attached to the shoe 10 in communication with the inflatable space of the tube portion 13 for admitting air under pressure intermittently to such space. The rubber and fabric parts of the inflatable shoe are united by vulcanization and pressure under heat.

In the operation of the inflatable shoe 10 under ice-forming conditions, air under pressure from a suitable source, which source may be disposed in the fuselage of the aircraft, for example, is admitted cyclically to the tube portion 13 through the interconnecting conduit 28 for expanding and contracting alternately the tube space. During a single cycle, for example, of inflating and deflating the tube portion 13, the tube assumes progressively several different forms such as the forms 29 and 30 shown by the broken lines in Fig. 1, while the stretchable portions 14 and 15 stretch progressively to a greater extent than that of the deflated condition and move relative to the airfoil 11 substantially throughout their extent. When the tube is fully inflated, the shoe 10 assumes substantially the position shown especially in Fig. 2.

The longitudinally extending side regions 25 and 26 and the inner wall 22 of the tube portion 13 being substantially restrained against stretching by the reinforcing fabric element 24, the sides of the tube portion bulge outwardly from the airfoil 11 assuming a condition of greater bulging or curvature with each increment of inflation which provides a rolling action of the sides of the tube portion 13 away from the airfoil 11 and progressively elongates chordwise the stretchable portions 14 and 15. In this manner ice formations are broken by the flexing of the side regions 25 and 26 of the tube and the stretching of the portions 14 and 15 reducing the adhesion of the ice thereto and facilitating ice removal by the ambient airflow.

While the sides of the tube portion are moving and bulging outwardly during inflation, the intermediate region 27 of the outer wall 23 immediately at the leading edge 12 is distended attaining a relatively highly stretched condition together with maximum change of curvature by virtue of the elasticity of the rubber-like material thereof, which action effectively diminishes the adhesion of the ice cap to the outer surface layer and fractures the ice cap immediately at the leading edge thereby unbalancing and moving laterally the broken ice relative to the airflow for removal by the ambient airstream. The co-operation of the tube portion 13 and the stretchable portions 14 and 15 thus provide effectively for the removal of ice accumulation on airfoils having thin-section leading edges despite the tendency of the ice under such conditions to resist dislodgment.

Variations may be made without departing from the scope of the invention as it is defined in the following claims.

I claim:

1. An inflatable shoe for preventing the accumulation of ice on an airfoil having a thin-section leading edge, said shoe comprising a tube portion of elastic material extending longitudinally of the shoe and stretchable portions of elastic material at the sides of said tube portion extending toward the margins of the shoe, said tube portion having an inner and an outer wall adapted to be distended upon inflation of the tube portion and said tube portion including a stretch-resisting fabric element in said inner wall and in longitudinally extending side regions of

said outer wall for resisting stretch of said inner wall and said side regions, said element having margins spaced apart in said outer wall leaving an intermediate region of said outer wall of relatively high stretchability.

2. An inflatable shoe for preventing the accumulation of ice on the leading edge of an airfoil, said shoe comprising a covering for disposition across the leading edge and to a rearward region 10 of said leading edge, said covering comprising an inflatable chamber having a forward wall distensible forwardly under inflation of said chamber and said covering comprising an attaching portion extending rearwardly from said forward wall, said attaching portion including a stretchable portion resiliently restraining the forward distention of said forward wall, and means comprising stretch-resisting material united with said covering and wholly disposed intermediate 15 said forward wall and said stretchable portion for locally restraining outward distention of the covering in the region of said stretch-resisting material while permitting the forward distention of said forward wall.

3. An inflatable shoe for preventing the accumulation of ice on the leading edge of an airfoil, said shoe comprising a covering for disposition across the leading edge and to a rearward region of said leading edge, said covering comprising an inflatable tube having a forward wall joining the back wall of the tube in the rear margin of the tube, said forward wall being distensible forwardly under inflation of the tube, and said covering comprising an attaching portion extending rearwardly from said forward wall at said rear margin of the tube, said attaching portion including a stretchable portion resiliently restraining the forward distention of said forward wall, and means comprising stretch-resisting material 30 united with said covering and disposed at said rear margin of the tube and wholly located intermediate said forward wall and said stretchable portion for locally restraining outward distention of the covering in the region of said stretch-resisting material while permitting the forward distention of said forward wall.

4. An inflatable shoe for preventing the accumulation of ice on the leading edge of an airfoil, said shoe comprising a covering for disposition across the leading edge and to rearward regions of said leading edge, said covering comprising an inflatable tube having a forward wall joining the back wall of the tube in rear margins of the tube, said forward wall being distensible forwardly 50 under inflation of the tube, and said covering comprising attaching portions extending rearwardly from said forward wall at said rear margins of the tube, said attaching portions including stretchable portions resiliently restraining the forward distention of said forward wall, and means comprising stretch-resisting material 55 united with said covering and disposed at said rear margins of the tube and wholly located intermediate said forward wall and said stretchable portions for locally restraining outward distention of the covering in the region of said stretch-resisting material while permitting the forward distention of said forward wall.

5. An inflatable shoe for preventing the accumulation of ice on the leading edge of an airfoil, said shoe comprising a covering for disposition across the leading edge and to a rearward region of said leading edge, said covering comprising an inflatable tube having a forward wall joining the back wall of the tube in a rear margin of the

tube, said forward wall having a front portion distensible forwardly under inflation of the tube, and said covering comprising an attaching portion extending rearwardly from said forward wall at said rear margin of the tube, said attaching portion including a stretchable portion resiliently restraining the forward distention of said front portion, and stretch-resisting material united with said covering at said back wall of the tube and extending into said rear margin and terminating to provide said front portion of said forward wall devoid of said material and for locally restraining outward distention of the covering in the region of said stretch-resisting material while permitting the forward distention of said front portion.

6. An inflatable shoe for preventing the accumulation of ice on the leading edge of an airfoil, said shoe comprising a covering for disposition across the leading edge and to rearward regions of said leading edge, said covering comprising an inflatable tube having a forward wall joining the back wall of the tube in rear margins of the tube, said forward wall having a front portion distensible forwardly under inflation of the tube, and said covering comprising attaching portions extending rearwardly from said forward wall at said rear margins of the tube, said attaching portions including stretchable portions resiliently restraining the forward distention of said front portion, and stretch-resisting material united with said covering at said back wall of the tube and extending into said rear margins and terminating to provide said front portion of said forward wall devoid of said material and for locally restraining outward distention of the covering in the region of said stretch-resisting ma-

terial while permitting the forward distention of said front portion.

7. An inflatable shoe for preventing the accumulation of ice on the leading edge of an airfoil, said shoe comprising a covering of rubber-like material for disposition across the leading edge and to rearward regions of said leading edge, said covering comprising an inflatable tube having a forward wall joining the back wall of the tube in rear margins of the tube, said forward wall having a front portion distensible forwardly under inflation of the tube, and said covering comprising attaching portions extending rearwardly from said forward wall at said rear margins of the tube, said attaching portions including stretchable portions resiliently restraining the forward distention of said wall, and stretch-resisting sheet fabric reinforcement embedded in said rubber-like material at said back wall of the tube and extending into said rear margins and terminating to provide said front portion of said forward wall devoid of said reinforcement and for locally restraining the outward distention of the covering in the region of said reinforcement while permitting the forward distention of said front portion.
